UNITED STATES PATENT OFFICE.

ASA L. CARRIER, OF WASHINGTON, DISTRICT OF COLUMBIA.

IMPROVED MODE OF ATTACHING FERRULES TO HANDLES.

Specification forming part of Letters Patent No. 70,694, dated November 12, 1867; antedated November 2, 1867.

To all whom it may concern:

Be it known that I, ASA L. CARRIER, of Washington, in the District of Columbia, have invented a new and useful Mode of Fixing Ferrules upon Tool-Handles, Canes, &c.; and I do hereby declare that the following is a full, clear, and exact description thereof, reference being had to the accompanying drawings, and to letters of reference marked thereon, in which—

Figure 1 is a plan view of the handle with the ferrule *b* set on the handle. Fig. 2 is a side view of the handle without the ferrule, showing the concave in it, into which the ferrule is pressed when put on, and portions of the shoulders *c c*. Fig. 3 represents the handle with the ferrule *b* set on, and *c c* portions of the shoulders. Fig. 4 is a vertical section through the handle and ferrule *b*.

The nature of my invention consists in the manner, hereinafter set forth, of attaching ferrules to handles of tools, umbrellas and parasols, and canes.

To enable others skilled in the art to make and use my invention, I will proceed to describe its construction and operation.

In constructing my ferrules I use material in common use for such purposes and make the ferrules as other ferrules are made. I then turn my handles in the usual form, and when thus turned up, as usual, I then turn out in concave form the shoulder to receive the ferrule, leaving about one-eighth of an inch or more untouched of the shoulder at each end of the same, thus forming a concave groove on the shoulder of the handle, as seen at Fig. 2. I then push the ferrule onto the handle, fitting tightly, and while the handle is still in the lathe I cause it to revolve, and with a suitable instrument bear moderately on the ferrule above the concave in the wood and spin down

the ferrule, causing it to fit closely and snugly to the handle, thus presenting a concave appearance when finished, as seen in Figs. 3 and 4 at *a* and *b*. Thus the operation is completed and my handles are ready for use.

It will readily be seen that when ferrules are thus set on handles it is impossible for them to work loose and fall off, which I find by experience to be the case with ferrules attached to handles, &c., in any of the modes in present use for fastening ferrules to tool-handles, either by rivets or by indentations of the ferrule into the wood by means of a punch or otherwise, as is the common practice.

It will be seen that if the wood should shrink after the ferrule is applied and snugly finished by spinning down into the concave on the handle, it is not possible for it to shrink sufficiently to allow it to get loose and fall off. This will be a great advantage to all mechanics using such tools as require ferrules on them, as they will not be liable to lose them off their tools. It will also be of great use in umbrellas and parasols, and they may also be attached to walking sticks or canes in the same way.

Having thus described the construction and operation of my invention, what I claim as new, and desire to secure by Letters Patent, is—

The ferrule *b*, constructed and applied to tool-handles, umbrellas, and canes, substantially as described, and operating as and for the purposes set forth.

In testimony that I claim the above-described invention I have hereunto signed my name this 22d day of August, 1866.

A. L. CARRIER.
